UNITED STATES PATENT OFFICE.

GEORGE W. GOSS, OF ST. LOUIS, MISSOURI, ASSIGNOR TO LUCENA M. MORDEN, OF WATERBURY, CONNECTICUT.

LOOSE-LEAF BINDER.

1,111,377.

Specification of Letters Patent. Patented Sept. 22, 1914.

Application filed January 29, 1912. Serial No. 674,078.

To all whom it may concern:

Be it known that I, GEORGE W. Goss, a citizen of the United States, residing at St. Louis, Missouri, have invented a certain new and useful Improvement in Loose-Leaf Binders, of which the following is a full, clear, and exact description, such as will enable others skilled in the art to which it appertains to make and use the same, reference being had to the accompanying drawings, forming part of this specification, in which—

Figure 1 is a plan view of a loose leaf binder of my improved construction. Fig. 15 2 is a cross section taken approximately on the line 2—2 of Fig. 1. Fig. 3 is a cross section similar to Fig. 2 and showing a modified form of the binder. Figs. 4 and 5 are cross sectional views similar to Figs. 2 and 20 3 and illustrating further modified forms of the binder. Fig. 6 is a detail plan view of a modified form of the binder and Fig. 7 is a detail section showing a construction wherein the adjustable ring-carrying member 25 engages the back plate of the binder.

This invention relates to a loose leaf binder of the type utilizing a back plate and a series of ring-carrying members that are adjustably positioned on the back plate. 30 By making the rings or loops adjustable toward and away from one another it is possible to accommodate the sheets or cards which vary in size and sheets or cards wherein the apertures are formed at different distances apart.

The principal object of my invention is to combine a series of rings or loops with a back plate and to provide simple means for simultaneously opening or closing all of 40 the rings or loops.

Referring by numerals to the accompanying drawings: 1 designates a back plate which is preferably constructed of sheet metal slightly curved in cross section and 45 having its side edges bent over on to the body portion of said plate, as designated by 2 to form retaining lips for the adjustable base plates 3 which carry the binding loops or rings. These base plates 3 are 50 preferably constructed of sheet metal approximately rectangular in outline and of such width as to fit snugly between the retaining lips 2 and to slide lengthwise upon the back plate when unlocked therefrom.

55 In the preferred form of the binder illus-

trated in Figs. 1 and 2 a pair of inverted U-shaped supports 4 are struck up from the central portion of each plate 3 and mounted upon pivot pins 5 which pass transversely through these supports are the lower ends 60 of a pair of curved arms 6 which unite to form a binding loop. The lower portions of these arms 6 extend inwardly toward one another from the pivot pins 5 and formed in the end of one of these lower ends is a 65 semi-circular seat 7, and formed in the corresponding end of the opposite arm is a notch 8.

9 designates a rod which is normally positioned between the lower ends of all of 70 the arms 6, and formed integral with this rod is a longitudinally disposed rib 10 which bears in the notches 8 and that portion of the rod directly opposite this rib bears in the curved seats 7. One end of this rod 9 75 is bent at right angles to the body portion thereof, as designated by 11 to form a handle whereby said rod may be partially rotated when the binding rings or loops are opened or closed.

80 The various parts of the form of binder just described are constructed so that when the arms 6 are closed to form binding loops the axis of the rod 9 occupies a plane slightly below the plane occupied by the 85 pivot pins 5, and thus when the rod is partially rotated so as to move downward below "center" the upper portions of the arms will swing together, thereby forming closed rings, and when so positioned said 90 arms are rocked for the reason that the rod is below the center of the fulcrumed points of said arms.

To simultaneously open all of the rings the operator engages the bent end 11 of the 95 rod and swings the same toward the left, thereby partially rocking said rod and in so doing the rib 10 bears against the lower portions of the arms 6 below the notches 8, and as a result, the opposite side of the rod 100 bears against the upper portions of the curved seats 7, thereby exerting upward pressure between the lower ends of both arms, and as a result, the rod is moved upward past "center" or above the plane occupied by the pivot pins 5, thereby simultaneously opening all of the rings or binding loops.

105 When the rings or binding loops are thus opened the outward pressure upon the sup- 110

ports 4 is relieved and as a result the frictional engagement between the outer edges of the plates 3 and the lips 2 of the back plate ceases and the base plates 3 are free to be adjusted toward or away from one another.

In the construction illustrated in Fig. 2 where the upper ends of the supports 4 are not connected the movement of the rod 9 downward below the pivot pins 5 tends to separate said pins and the supports 4, and such action springs the side edges of the plates 3 downward, thereby causing the same to frictionally engage in the grooves beneath the lips 2 on the sides of the back plate 1, and when the rod 9 is moved upward above the plane occupied by the pivot pins to open the binding loops, this frictional engagement is relieved and the plates 3 are free to be adjusted lengthwise on the back plate.

To simultaneously lock all of the binding loops the rod 9 is rotated toward the right thereby bearing down upon the lower portions of the curved seats 7, and as a result, the rod passes below "center" and the upper ends of the arms 6 are swung together to form the closed binding rings or loops.

30 In the modified construction illustrated in Fig. 3 a perfectly smooth rod 9^a occupies a position between curved seats formed on the lower ends of both of the arms 6, which rod is adapted to move above and below the plane occupied by the pivot pins or fulcrums of said arms when the arms are opened or closed. The rod 9^a is moved upward to open the arms by means of pressure applied to a pin 12 which operates through 40 the back plate 1 and bears directly against the underside of said rod 9^a. In the form shown in this figure as well as in Figs. 4 and 5 the parts 4 shown in Fig. 2 are connected at the top to form an integral yoke. 45 This back-plate through which the pin 12 extends guides the pin, detachment thereof being prevented by a part of the back 1^a which passes over the head of the pin and which is usually of flexible formation.

50 In the modified construction illustrated in Fig. 4 a rod 13 which is quarter round in cross section is positioned between the lower ends of the arms 6 and the rectangular faces of said rod engage the lower end of one of 55 the arms and the curved face engages the lower end of the opposite arm. To open and close the arms in this form of the device the rod 13 is rocked in the same manner as the rod 9 in the construction shown in 60 Figs. 1 and 2.

In the construction illustrated in Fig. 5 an operating member 14 formed of sheet metal performs the function of a rod, said operating member being provided with a 65 tongue 15 which engages in a notch formed

in the lower end of one arm and the rounded portion of said operating member engages the curved seat in the lower end of the opposite arm. In this form of device the operating member is partially rocked to effect an opening or closing movement of the arms. 70

In the modified construction illustrated in Fig. 6 the edges of the inwardly projecting lips 2 are notched or serrated, as designated by 16, and the outer edges of the supports 4 engage said notched or serrated edges when the arms are closed, thereby locking the base plate in its adjusted position. Where this construction is employed the friction of the side edges of the base plate 3 is not depended upon to maintain 80 said base plate in its adjusted position.

In the modified construction illustrated in Fig. 7 the inner faces of the grooves beneath the retaining lips 2 are corrugated as 85 designated by 17 and these corrugated or serrated portions are engaged by the corrugated or serrated outer edges of the plates 3 when the arms are closed, thereby effectually locking the base plates to the back plate. 90

A loose leaf binder of my improved construction is comparatively simple, can be very cheaply manufactured inasmuch as but very few parts are required to provide a complete fixture or binder and by providing binding loops which are adjustable toward and away from one another a single binder or fixture can be utilized for receiving cards or sheets of different size and cards or sheets wherein the apertures are formed at 100 different distances apart.

It will be readily understood that minor changes in the size, form and construction of the various parts of my improved loose leaf binder may be made and substituted for those herein shown and described without departing from the spirit of my invention, the scope of which is set forth in the appended claims.

I claim:

1. In a loose leaf binder a back plate, a series of base plates adjustably positioned on the back plate, a pair of arms fulcrumed on each base plate each pair of arms uniting to form a binding loop and means co-operating with the pairs of arms for simultaneously moving the same into opened or closed positions. 110

2. In a loose leaf binder a back plate, a plurality of base plates adjustably arranged on the back plate, a pair of arms fulcrumed on each base plate, which arms unite to form a binding loop and a member arranged between the lower ends of all of the arms for simultaneously moving the same into 115 opened or closed positions. 120

3. In a loose leaf binder a back plate, a plurality of base plates adjustably positioned thereon, a pair of arms fulcrumed on each base plate, which arms unite to form 130

- a binding loop and a rod positioned between the lower ends of all of the arms for simultaneously actuating the same.
4. In a loose leaf binder a back plate, a plurality of base plates adjustably positioned thereon, a pair of arms fulcrumed on each base plate and adapted to form a binding loop and a rod positioned between the lower ends of all the arms, and which 10 rod is adapted to move above and below the plane occupied by the fulcrums of the arms for the purpose of simultaneously opening and closing said arms and locking the base plates to the back plate.
- 15 5. In a loose leaf binder the combination with a back plate, of a pair of base plates adjustably positioned on the back plate, a separable binding loop on each base plate and a locking member coöperating with the 20 binding loop for simultaneously opening or closing the same and for locking the base plates to the back plate when the binding loops are closed.
6. In a loose leaf binder a back plate, a plurality of base plates adjustably positioned thereon, a pair of arms fulcrumed on each base plate which arms unite to form a binding loop, and a rocking rod between the lower ends of all of the arms for simultaneously 30 actuating all of the same.
7. In a loose leaf binder, the combination of a back plate, a series of members adjustably positioned on the back plate and having upstanding portions, a series of binding 35 loops or rings, pivot pins connecting said rings with said upstanding portions back from the opposed ends of said rings so that such ends project inwardly beyond such pivot pins, and means coöperating directly 40 with the lower opposed ends of said rings whereby the latter will simultaneously open and close.
8. In a loose leaf binder the combination of a back plate, a series of base plates adjustably positioned on the back plate, each having an upstanding portion, a pair of arms pivotally connected to said upstanding portion, and means coöperating with the 45 ends of said arms for simultaneously moving the same into their opened or closed positions.
9. In a loose leaf binder the combination of a back plate, a plurality of pairs of pivotally supported arms carried thereby, each 50 pair uniting to form a ring, said rings sup-
- ported for adjustable movement toward and from one another, the lower opposed ends of said arms constructed to receive an angularly formed member, and a rod having an angular portion located between the ends of 60 said arms for simultaneously opening and closing the same.
10. In a loose leaf binder the combination of a back plate, a plurality of base plates adjustably positioned on the back plate, a pair of arms fulcrumed on each of said base plates, and means operative to simultaneously open or close the arms, said base plates and back plate having means for locking the base plates against movement. 70
11. In a loose leaf binder the combination of a back plate, a plurality of base plates adjustably positioned on the back plate, a pair of arms fulcrumed on each of said base plates, and means operative to simultaneously open or close the arms, said base plates and back plate having serrated means for locking the base plates against movement. 75
12. In a loose leaf binder the combination of a back plate, a plurality of base plates adjustably positioned thereon, a pair of arms fulcrumed on each base plate to form a binding loop, means coöperating with the several pairs of arms for simultaneously opening and closing the same, and interlocking means carried by the base plates and back plate for locking the base plates against movement. 80
13. In a loose leaf binder the combination of a back plate, a plurality of pairs of non-integrally connected loop forming arms carried thereby, means for simultaneously opening or closing all of said arms and having means extending transversely through the back plate and in position to be operated. 85
14. In a loose leaf binder the combination of a back plate, a plurality of pairs of loop forming arms supported thereby for adjustable movement toward and from one another, means for simultaneously opening and closing all of said arms, and means extending through the back plate for manipulating said opening and closing means. 95
